UNITED STATES PATENT OFFICE.

NATHANIEL WHEELER, OF BRIDGEPORT, CONNECTICUT.

DESIGN FOR A RAILWAY-CAR.

SPECIFICATION forming part of Design No. 13,712, dated March 6, 1883.

Application filed November 27, 1882. Term of patent 14 years.

To all whom it may concern:

Be it known that I, NATHANIEL WHEELER, a citizen of the United States, residing at Bridgeport, in the county of Fairfield and State of Connecticut, have invented and produced a new and original Design for Railway-Cars, of which the following is a specification, reference being had to the accompanying drawing, forming part thereof.

- 10 The drawing represents in perspective an interior view of a section or a sufficient portion of a car to illustrate my novel design.
- 15 Commencing with the wainscoting A, which has a top piece, a, extending in a straight line from end to end of the car, I have erected a series of pilasters, B, that extend to the ceiling C, which, instead of being concaved, as usual, and terminating at about the level of the top of the door of the car, is nearly horizontal or 20 but slightly inclined, thus affording an additional space above the windows E for decorative purposes. Between the heads b of the adjacent pilasters I have placed a molding, b², and between the sides of adjacent pilasters, below the molding b², I have made panels d, and below the panels I have placed a molding, d², which projects out beyond the pilasters. Below the molding d², I have mitered together pieces of molding to form a receding space or 25 transom, e, in which I have placed a sash, e², having a stained, decorated, or colored glass window, e³. Below the transom-window is a straight stationary rail, f, which forms a dividing-line between the decorated transom-windows and the curtains g below it, which latter cover more or less of the row of windows E. The curtain has an ornamental transverse stripe, h. At the side of the ceiling farthest from the pilasters and side wall of the car is a 30 portion, H, inclined upward at an angle of about forty-five degrees from the ceiling C, and provided at bottom and top with lines of molding h². Above the inclined portion H rises the short pilasters I, having between them the ornamental stained-glass windows m, and above the window-caps and pilasters I is the ceiling n of the roof or deck of the car. The pilasters B are crossed by pieces f², of wood, of the same width as the rail f, so as to form a continuous 35 rail or bar, and at the junction of pieces f² and the rail f are ornaments f³.

In designing the interior of the car I have studied to present a series of longitudinal lines of decoration, the most noticeable and effective of which are the rows of moldings d², projecting from between the pilasters, the rows of decorated windows e² and m, the fixed straight rail f between windows e² and E, the row of panels d between the ceiling C and the windows e², and the row of curtains g below the transom-windows and rail f, and the transverse ornamental stripes h of the curtains.

A car such as herein shown presents a very pleasing and striking appearance.

The ceiling C, inclined portion H, and ceiling n are subdivided transversely by strips 2 3 4 of molding, thus forming the ceiling C, portion H, and ceiling n into small and large panels as shown. The windows E, curtains, ornamented transom-windows, panels d, and windows m are in the same vertical line.

The leading features of my design are the parallel horizontal rows of windows e² E and rows of windows separated by the vertical pilasters, and the row of curtains g, starting from below the rail f, and between the transom-windows and large windows E and the straight rail f.

The transom-windows e² are never covered by the curtains g, but are always exposed.

The shape of the molding employed and the particular figures represented upon the stained-glass windows may be varied without departing from my invention.

I claim—

1. The design for the interior of a railway-car, consisting of the row of windows E, the row of curtains g, the row of transom-windows e² above the curtains, and the rail f between the curtains and the transom-windows, and the vertical pilasters separating adjacent windows E e² and curtains, as herein shown.

2. The design for interior of a railway-car, as herein shown, consisting of the row of windows E, the line of rail f, the row of ornamented transom-windows e² above the rail, the moldings d², and the row of panels d, above the said molding.

3. The design for the interior of a railway-car, it consisting of the row of windows E, the row of ornamented windows e², the row of curtains starting from between the windows E

and e^2 , the ceiling C, the row of ornamented windows m, and the pilasters B and I, dividing adjacent windows of the rows of windows, as herein shown.

5 4. The design for the interior of a railway-car, it consisting of the wainscoting A, the row of windows E, the row of curtains having ornamented stripes h, the rail f, the row of ornamented windows e^2 , and the row of panels d, appearing in the order mentioned at the side of the car and below the ceiling, as herein shown.

5 5. The design for interior of a railway-car, it consisting of the row of windows E, the row of ornamented windows e^2 above the row of curtains starting from between the windows E and e^2 , the moldings d^2 above windows e^2 , the pilasters B, and the cross-pieces f^2 and rail f in the same line, as herein shown.

6. The design for the interior of a railway-car, it consisting of the row of windows E, curtains g, rail f, ornamented windows e^2 , panels d, the projecting molding d^2 between the windows

downs e^2 and panels d, the vertical pilasters B, the molding b^2 between the panels d and ceiling, the ceiling C, and inclined portion H, the cross-pieces 2 3 to divide the ceiling and portion H into panels, the row of windows m, and the pilasters I, dividing them, all as herein shown.

7. The design for interior of a railway-car as herein shown, consisting of the adjacent rows of windows E e^2 , one above the other, pilasters to separate the windows of adjacent rows, and the straight line of rail f, fixed to the car-body and separating the windows E and e^2 , as shown and described.

In testimony whereof I have signed my name to this specification in the presence of two subscribing witnesses.

NATHANIEL WHEELER.
